David S. Roseman, New York, N. Y.

Application May 13, 1936, Serial No. 62,621

Term of patent 3½ years

To all whom it may concern:

Be it known that I, David S. Roseman, a citizen of the United States of America, residing in Manhattan, county of New York, and State of New York, have invented a new, original, and ornamental Design for a Bolero Sweater Ensemble, of which the following is a specification, reference being had to the accompanying drawings, forming part thereof, wherein,

Figure 1 is a front view of a bolero sweater ensemble showing my new design.

Figure 2 is a rear view of the bolero sweater ensemble shown in Figure 1.

The characteristic feature of my design resides in the combination on a twin sweater ensemble of a bolero jacket having a knitted braid trim around the front edges thereof, and a coarse ribbed back band. The inner sweater is conventional, except for the fancy knit front as shown.

I claim:

The ornamental design for a bolero sweater ensemble, substantially as shown.
